UNITED STATES PATENT OFFICE.

MANES I. HAMBURGER, OF BALTIMORE, MARYLAND.

UMBRELLA BUST-FORM.

1,107,062.

Specification of Letters Patent. Patented Aug. 11, 1914.

Application filed March 19, 1913. Serial No. 755,406.

To all whom it may concern:

Be it known that I, MANES I. HAMBURGER, a citizen of the United States, residing at Baltimore city, in the State of Maryland, 5 have invented certain new and useful Improvements in Umbrella Bust-Forms, of which the following is a specification, reference being had therein to the accompanying drawing.

10 My invention consists of a collapsible bust form of what may be called the umbrella type. It is characterized by the provision of a number of vertically extending bendable ribs connected at one end to a common 15 central supporting member and extensible therefrom to form a frame of the bust form through their connection by struts with a sliding member on a central stem support.

Bust forms are very irregular in section 20 and contour. My invention includes means to take care of these variations whereby a form of this type may be made of any variety of sections and contours. Specifically stated in accordance with the embodiment 25 which I shall herein disclose, this is very simply accomplished by connecting the struts between the ribs and the sliding member on the support at one end for sliding movement with respect to the connected 30 part.

The base of the form of my invention may be also characterized as being of the umbrella type in that a plurality of radially extensible feet are pivoted at one end to the 35 lower extension of the supporting stem, and may be collapsed to a position parallel and contiguous to the stem itself. The stem support is separable into sections whereby the entire form may be packed when folded into 40 a space only two or three times greater than that of the ordinary hand umbrella.

Referring to the drawings, Figure 1 is a central vertical and transverse section of the form of my invention showing the same extended. Fig. 2 is a vertical section taken from front to back and also showing the form extended, Fig. 3 is a central vertical transverse section showing the same collapsed together with the stem support separated into sections, Fig. 4 is a horizontal transverse section. Fig. 5, 6, and 7 are details.

Referring first to Figs. 1, 2 and 4, it will be seen that the form of my invention comprises 55 a plurality of vertically extending ribs 10—10' which are hinged at their upper ends to

a central supporting stem 11. They are not hinged directly to the stem, but to an enlargement 12 of the stem which is of circular shape and adapted to constitute a neck portion of the form. Through struts 13 of various lengths, the ribs 10—10' are connected with a sliding tubular member 14 on the central stem 11. Through the movement of this tubular member up and down on the stem, the form may be extended and collapsed.

The side ribs 10' are different from the front and back ribs 10 (see Fig. 4 and Figs. 1 and 2). The front and back ribs 10 are made of continuous flexible strip material, and are perfectly flat in cross section as shown in Fig. 4. The side ribs 10 however are made in a plurality of rigid or semi-rigid sections hinged together at certain points to form joints 14' and adapted when extended to form the contour of the sides of the bust. The hinged joints 14' are located at such points as will enable the ribs 10' when collapsed as shown in Fig. 3 to most closely approximate a straight line, thus being at the nodal points, or points of greatest convexity of the curves. The struts 13 extending to the sides are connected at these hinged joints as clearly shown.

85 The connection of the struts 13' with the tubular sliding member 14 is made through slots 15 in the tube and of varying length as shown in Figs. 1 and 6. Struts 13' are those struts which partake of maximum movement less than the maximum movement of the sliding member 14. The diameter of the tube 14 is greater than the diameter of the stem 11 so that an annular space is left between them. The ball-shaped ends 16 of the 90 struts lie within this space, and are of too large a diameter to pass out of the slots 15. They may be initially entered within the slots in any chosen manner, as for instance by enlarging one end of each slot and thereafter closing it up, or by forming a small flap section 17, which may be bent outwardly and then inwardly again as shown in Fig. 6. If desired, the struts 13' may be inserted from the inside of the tube 14 outwardly before the tube 14 is assembled upon the stem 11. On account of the length of the slots 15 this may be very readily done, the rib ends of the struts being made small enough to pass through the slots 105 15. The relative lengths and relative locations of the slots 15 are made such that the

short length struts do not interfere in any way with the full movement of the tubular member 14 necessary for a complete collapse of the portions of the form which lie 5 the greatest distance from the stem 11. Thus the slots 15 in which the struts having the least movement are pivoted, are made sufficiently longer than the slots in which struts having the greater movement are piv- 10 oted to freely permit complete movement of the latter struts. The length of all slots is regulated with respect of course to the maximum movement of the tubular member 14. Thus the shoulder portions which are 15 braced in extended position by the upper struts 13 must be moved a much greater distance through movement of the sliding member 14 than the breast, back and waist portions. The bottoms of the slots 15 are at 20 such points that when the sliding member 14 is in its uppermost position, the inner ends of the struts 13 are braced against the bottoms and in turn brace the ribs to which 25 they are connected to their fully extended positions.

Obviously the struts 13 having the greatest extent of movement, such for instance as the struts connected with the shoulder portions, may be fixedly hinged to the sliding member 14 as shown in Fig. 4 instead of being slidably hinged thereto through slots 15. So also the lowermost struts 13 of Fig. 1 connecting with the hip portion of the form and which have a movement substantially equal to the uppermost struts 13, may be fixedly pivoted to the member 14. Still further the lateral waist struts of Fig. 1 when the waist is not too small may be fixedly connected to the member 14 by locating 40 the pivot at a point which, when the member 14 is uppermost, lies above the transverse line connecting the hinged joints of the ribs a distance equal to the distance between the extent of movement of the shoulder struts 13 and the waist struts 13. Under 45 these conditions the slight stretching of the waist of the form as the waist struts pass the horizontal line is not great. When the waist is small however, the struts should be 50 slidably connected at one end as are the struts of the front and back of the form. Fixedly pivoting certain of the struts 13 gives a stability greater than may be secured through slidably connecting all of 55 them.

The lateral ribs 10' are padded by material 18 as clearly shown in Figs. 1 and 5. The entire frame is covered with burlap or other suitable fabric 19 as clearly shown in 60 Fig. 4, this fabric being sewed together in sections in a manner very similar to the sewing together of a tightly fitting jacket or gown, and suitably attached to each of the several ribs so that there is no harmful dis- 65 placement thereof when the form is col-

lapsed. Wherever there is strain liable to be imposed when the form is collapsed, the fabric may be loosely secured to one of the adjacent ribs whereby strain may be relieved through movement of the fabric with respect to the ribs. The stem 11 is made in upper and lower sections, the lower section 11' having a socket connection with the upper and being secured thereto by means of a thumb screw 20.

The base of the form comprises the three radially extending feet 21 which are hinged to the lower end of the section 11' at their inner ends, and while they have free movement upwardly to a position parallel and 70 contiguous to the section 11' as shown in Fig. 3, they have a limited amount of movement only below the horizontal. When in extended position as shown in Fig. 1, they are retained therein by means of a sliding 80 collar 22 on the section 11' which engages in notches 23 in each of the feet 21, and which may be clamped into position upon the section 11' by thumb screw 24. Upon releasing the thumb screw 24, the collar 22 may be 90 moved upwardly to permit the folding of the feet as shown in Fig. 3, whereupon the clamping collar 22 may be pushed over the outer ends of the feet, the collar being of such diameter that it fits readily over the 95 chamfered outer ends of the feet. The feet are thus retained in their collapsed position.

When both the bust and its base are collapsed as shown in Fig. 3, they may be strapped tightly together in a common bundle of very small size, and may be most readily transported in a suitable case by hand, or in a suit case or trunk. In any case, it takes up but a very small space. Whenever it is desired to use the form, one has 100 only to unstrap the same, extend the base section 11', and place it upon the floor or table, and thereupon grasping the stem 11 with one hand and the sliding member 14 with the other, open the form in the same 105 manner as one would an ordinary umbrella, and with the same celerity. Opened, it is placed upon the base section 11' and secured thereto by the thumb screw 20. It will be 110 observed that the form is held in open position by a latch 25 of the same form that is found in the ordinary umbrella. The form may as readily be collapsed. On account of its lightness and the small space it occupies, several of them of different sizes may be 115 carried by salesmen without encumbering their baggage in any way.

Fig. 7 illustrates in transverse section a wooden sliding member 14, provided with undercut slots 15' in its surface. In this case, the struts 13 connected with the sliding member 14 are made with T-heads on the ends as clearly shown. Any other equivalent construction desired may be used.

Although I have shown the best form of 130

my invention now known to me, I desire to have it understood that my invention is capable of many modifications without departing in any wise from its generic spirit.

5 I desire to cover in the annexed claims all such embodiments of my invention.

Having thus described my invention what I claim and desire to secure by Letters Patent is:

10 1. A collapsible form comprising a central vertically extending support, a plurality of vertically extending bendable ribs connected at one end to said support, a sliding member on said support having a plurality of axially extending slots varying in length in its exterior walls, and a plurality of struts of varying lengths extending freely between said ribs and said sliding member each connected at one end slidably in one of said 20 slots and at the other end pivotally to one of said ribs.

2. A collapsible form comprising a central vertically extending support, a plurality of vertically extending bendable ribs connected at one end to said support, a sliding member on said support, and a plurality of struts of varying lengths extending freely between said ribs and said sliding member and connected at one end slidably in slots of varying 30 lengths and at the other end pivotally.

3. A collapsible form comprising a central vertically extending support, a plurality of vertically extending bendable ribs hinged at the top to said support, a sliding member 35 on the support said sliding member having a plurality of axially extending slots in its exterior walls, and a plurality of struts of varying lengths extending freely between said ribs and said sliding member and connected at one end slidably in said slots and at the other end pivotally to said ribs, the ends of said slots forming abutments for the inner ends of said struts.

4. A collapsible form comprising a central vertically extending support, a plurality of vertically extending bendable ribs hinged at the top to said support, a sliding member on the support and a plurality of struts of varying lengths extending freely between said ribs and said sliding member and connected at one end pivotally with said ribs and at the other end slidably to said sliding member on the support.

5. A collapsible form comprising a central vertically extending support, a plurality of vertically extending bendable ribs hinged at the top to said support, a sliding member on the support and a plurality of struts of varying lengths extending freely between said ribs and said sliding member and connected at one end to said ribs and at the other end to said sliding member, at one end pivotally and at the other end slidably.

6. A collapsible bust form comprising a central vertically extending support, a plu-

rality of vertically extending bendable ribs hinged at the top to said support, the side ribs being composed of rigid sections hinged to each other and adapted when extended to take the desired shape of the side of the 70 form.

7. A collapsible bust form comprising a central vertically extending support, a plurality of vertically extending bendable ribs hinged at the top to said support, the side 75 ribs being composed of rigid sections hinged to each other and adapted when extended to take the desired shape of the side of the form, the front and back ribs being of continuous flexible strips.

8. A collapsible form comprising a central vertically extending support, a plurality of vertically extending collapsible ribs hinged at the top to said support, the side ribs being composed of rigid sections hinged to each 85 other and adapted when extended to take the desired shape of the side of the form, said sections being formed respectively of those portions approximating most closely straight lines, whereby the rib when collapsed approximates most closely a straight line.

9. A collapsible form comprising a central support, a plurality of collapsible ribs pivoted at one end to said support and movable 95 from a collapsed position substantially parallel thereto, to an extended position spaced apart therefrom, said ribs being divided into a plurality of permanently curved sections hinged together, the points of division being 100 such as to enable said ribs when collapsed to most closely approximate a straight line, a sliding member on the support, and struts connected pivotally with said ribs and said sliding member.

10. A collapsible form comprising a central vertically extending support, a plurality of vertically extending bendable ribs connected at one end to said support, a sliding member on the support having a plurality of axially extending slots of varying lengths the bottoms of which lie in various axial positions, and a plurality of struts of varying lengths extending freely between said ribs and said sliding member and connected at one end pivotally to said ribs and at the other end slidably in said slots, the bottoms of said slots constituting abutments by means of which said struts are moved.

11. A collapsible form comprising a central vertically extending support, a plurality of vertically extending bendable ribs connected at one end to said support, a sliding member on the support having a plurality of axially extending slots of varying 120 lengths the bottoms of which lie in various axial positions, and a plurality of struts of varying lengths extending freely between said ribs and said sliding member and connected at one end pivotally to said ribs and 125

4
at the other end slidably in said slots, the bottoms of said slots constituting abutments by means of which said struts are moved, and the struts having the least movement being connected with the sliding member through slots having the greatest length.

12. A collapsible bust form comprising a central vertically extending support, a set of vertically extending bendable ribs connected at one end with said support, the side ribs of said set being composed of rigid sections hinged to each other and adapted when extended to take the irregular shape of the shoulders and sides of the form, a sliding member on the support within the form, and lateral struts interconnecting the ribs and the sliding member and extending freely between said ribs and said sliding member.

20 13. A collapsible bust form comprising a central vertically extending support, a set of vertically extending bendable ribs connected at one end to said support, a sliding member on said support inside of the ribs, laterally projecting struts interconnecting said ribs and said sliding member and extending freely between said ribs and said sliding member, the struts interconnecting the side ribs and the sliding member having a fixed pivotal connection at each end, whereas the struts interconnecting the front and back ribs with the sliding member have a fixed pivotal connection at one end and a slidable connection at the other.

35 14. A collapsible form comprising a vertically extending support, a plurality of

vertically extending bendable ribs connected at one end with said support, a sliding member on said support, and struts of varying lengths interconnecting said ribs and said 40 sliding member and arranged through movement of said sliding member on said central support to impart to each of said bendable ribs movements varying in degree, those struts imparting the greatest degree of 45 movement to said ribs having a fixed pivotal connection with both the ribs and the sliding member, while the struts imparting lesser degrees of movement have a fixed pivotal connection at one end and a sliding 50 pivotal connection at the other end.

15. In combination a collapsible form, a vertically extending support therefor, and a base for said support comprising radially extending feet pivotally connected to the 55 lower end of the base and movable into and out of the folded position parallel to said support without removing the same from the support, together with a collar sliding on said support and disconnected from said 60 feet but having laterally disposed surfaces arranged to engage said feet and retain the same in both extended and collapsed positions when the collar is moved axially to said support into juxtaposition on said feet. 65

In testimony whereof I affix my signature in presence of two witnesses.

MANES I. HAMBURGER.
